United States Patent Office.

W. WEUSTHOFF AND CHARLES SCHMIDT, OF DAYTON, OHIO.

Letters Patent No. 96,064, dated October 19, 1869.

IMPROVEMENT IN GRAIN-DRILLS.

The Schedule referred to in these Letters Patent and making part of the same.

To all whom it may concern:

Be it known that we, W. WEUSTHOFF and CHARLES SCHMIDT, of Dayton, in the county of Montgomery, and in the State of Ohio, have invented certain new and useful Improvements in Grain-Drills; and do hereby declare that the following is a full, clear, and exact description thereof, reference being had to the accompanying drawing, making a part of this specification, in which—

Figure 1 is a front elevation of our improved devices;

Figure 2 is a vertical cross-section on the line xx of fig. 1;

Figure 3 is a perspective view of the slide for closing the opening in the bottom of the hopper; and

Figure 4 is a like view of the plate used for holding the seed-wheel in place.

Letters of like name and kind refer to like parts in each of the figures.

Our invention relates to a class of drills in which the seed-wheels are expansible longitudinally; and

It consists in the employment of a slide within the bottom of the hopper, which, being connected to and moving longitudinally with the movable portion of the seed-wheel, causes the opening in the bottom of said hopper to correspond in length with the grooves within said seed-wheel.

In the annexed drawing—

A represents the bottom of the hopper, secured to the lower side of which is the seed-wheel box or casing B, having the general form shown in figs. 1 and 2.

The central portion of the seed-wheel C consists of a short cylinder, provided with a series of longitudinal grooves, at each end of which is placed a circular disk, D, so as to form a series of cups for containing the grain.

In order that the length of the grooves or cups may be varied, the cylindrical portion of the wheel is divided through its centre, longitudinally; and one end of each section, c, is secured to one of the disks, while its opposite or outer end passes through a suitable opening in the opposite disk, so as to permit said disks to be moved to or from each other at will.

As thus constructed, the seed-wheel is placed upon the shaft E, and one section permanently attached thereto, and the whole placed within the box B, the inside length of which corresponds with the length of the wheel.

One end of the box B is enclosed, except where the shaft passes through, while the opposite end is provided with a suitable opening for the admission thereto of the wheel, which is so placed within as that the disk of the loose section shall be at said open end.

An angle-plate, F, is secured to the hopper-bottom A, and extends downward, so as to embrace the edge of the outer face of said disk and hold the section to which it is attached within the seed-wheel box, while, at the same time, allowing said section to revolve freely with the shaft.

When thus arranged, the relative positions, longitudinally, of the loose section of the seed-wheel and of the box B, do not change; but the section secured to the shaft, together with said shaft, may be freely moved from one end of said box to the other, and the length of the grooves within the wheel correspondingly changed.

Immediately above the seed-wheel box B is an opening, a, in the hopper-bottom A, corresponding in length and breadth with the size of said box, through which seed is admitted from the hopper.

A metal plate, G, is placed immediately beneath said opening, and slides longitudinally within suitable grooves, b and b, at the upper side of the seed-wheel box B, while its outer end is supported and guided by means of a screw or stud, a', passing upward through a longitudinal slot, g, in said plate, into the hopper-bottom.

Secured to and projecting downward from the forward end of the slide G, is a curved lug, H, the inner edge of which conforms to the shape of and fits into a groove, d, cut in the periphery of the disk of the section D, secured to the shaft, so that while allowed to revolve freely, if said disk and shaft are moved longitudinally, a corresponding motion of the slide is produced, by which means the relative lengths of the grooves within the periphery of the seed-wheel, and of the opening a in the hopper-bottom, at all times correspond.

I represents a longitudinal opening in or through the front wall of the seed-wheel box B, for the passage therethrough of the seed.

The upper edge of the opening is straight and horizontal, as shown in the drawing, while the lower edge consists of two or more planes, i, arranged in the manner of saw-teeth, or at an angle with the line of the seed-wheel.

The object of this form of opening is to render more uniform the flow of seed from the box B into the funnel, which result it accomplishes by slightly checking the flow of said seed, and causing it to pass from said opening at a number of points, instead of allowing the amount brought forward by each groove to fall at once into the ground; as, in the latter case, the contents of each groove would be deposited in one place, instead of being evenly distributed with the contents of the other grooves.

These improvements add greatly to the efficiency of the seed-drill, without increasing its cost, and it

is believed that when known to the public, their general adoption may be expected.

Having thus fully set forth the nature and merits of our improvement,

What we claim as new, and desire to secure by Letters Patent, is—

The slide G, provided with the lug H, in combination with the opening in the hopper-bottom A, and with the seed-wheel C, substantially as and for the purpose specified.

In testimony that we claim the foregoing, we have hereunto set our hands, this 30th day of August, 1869.

W. WEUSTHOFF.
CHARLES SCHMIDT.
